CONTAINER

Alvin J. Byrne, Brooklyn, N. Y., assignor to American Can Company, New York, N. Y., a corporation of New Jersey

Application October 25, 1935, Serial No. 46,779

6 Claims. (Cl. 220—31)

The present invention relates to a hinged cover container and has particular reference to such a container in which the cover is laterally slidable along its hinge so that it may be locked in closed position upon the container by cooperating interlocking projections and indentations which are readily disengaged when opening the container.

An object of the invention is the provision of a simple and economically produced container having a body and a hinged cover with a depending flange which overhangs the body side walls, the cover being also laterally slidable along its hinge connection to lock it in closed position by cooperation of bayonet joint projections and indentations formed in the cover flange and in a corresponding body side wall.

Another object of the invention is the provision of such a container wherein its interlocking bayonet joint projections and indentations are further locked against inadvertent disengagement when the cover is in its fully closed and locked position.

Numerous other objects and advantages of the invention will be apparent as it is better understood from the following description, which, taken in connection with the accompanying drawing, discloses a preferred embodiment thereof.

Referring to the drawing:

30 Figure 1 is a perspective view of a hinge cover container embodying the instant invention, the view illustrating the hinge cover in partially opened position;

35 Fig. 2 is a front elevation of the container illustrated in Fig. 1 showing the cover in fully closed and locked position;

Fig. 3 is a rear elevation of the container with the cover in fully closed and locked position;

Fig. 4 is an enlarged transverse section taken 40 substantially along the line 4—4 in Fig. 2, with parts broken away; and

Fig. 5 is an enlarged fragmentary horizontal detail section taken substantially along the line 5—5 in Fig. 2 and illustrating one corner of the 45 container adjacent its front edge.

The drawing illustrates the invention as preferably embodied in a rectangular container 11 comprising a shallow open top body 12 which is adapted to be closed by a hinge cover 13. The 50 body is preferably drawn from a single piece of sheet material and includes substantially parallel end walls 15 and front and rear walls 16, 17, which are joined to the side walls in rounded corners these walls merging into a bottom wall 55 18.

The cover 13, like the body, is preferably formed from a single piece of material and comprises a flat top wall 21 which merges into a depending skirt or peripheral flange 22 constituting a single end and front and rear wall which overhangs the corresponding body walls when the cover is in its closed position. That portion of the flange which is adjacent the body end wall 15 is substantially cut away for a purpose hereinafter explained, what is left of the flange being 5 bent back as in a hem 23 which lays against the under side of the cover and presents a smooth edge adjacent the body end wall.

The cover 13 is hinged to the body 12 in a pintle hinge connection 24 (Figs. 3 and 4). This hinge connection comprises a pair of spaced pintle lugs 26 struck out from the body rear wall 17 and these carry the ends of a pintle rod 27. Adjacent the lugs 26 the flange rear wall of the cover is cut away to form lug clearance notches 28, 29. A hinge lug 31 disposed between the notches surrounds the pintle 27 and is freely movable thereon, the body rear wall 17 between the lugs 26 being curved inwardly to provide clearance for the lug 31 and to permit free hinging of the cover on the pintle.

By reason of this hinge construction, the cover 13 may be shifted or slid endwise or axially on the pintle 27 relative to the body 12 the hinge lug 31 being made narrower than the 30 space between the pintle lugs 26 as shown in Fig. 3. This is the purpose of the cut away part of the cover flange end wall, which is adjacent the body wall 15, as hereinbefore mentioned.

The combined hinging and sliding movement 35 of the cover on the pintle is provided so that the cover after being closed on the body may be locked in that position. The body front wall 16 and the corresponding cover flange front wall 22 are provided with cooperating indentations 40 and projections which interlock when the cover is fully closed and locked but which may be readily disengaged for opening the container.

The cover flange front wall 22 is formed with a pair of spaced inwardly bent lugs or projections 34 (Figs. 1, 2, 4 and 5) one adjacent each of the rounded corners on the front of the cover. In closing the cover these lugs 34 are first aligned with a pair of spaced bayonet or L-shaped grooves or indentations 35 which are formed in the front wall 16 of the body, this being accomplished by bringing the free or front edge of the cover nearly down to the body edge as in Fig. 1. The lugs are then moved down into the indentations as the cover is closed.

Each indentation comprises a vertical groove 36, the upper end of which is open at the top edge of the body wall and a horizontal locking groove 37 which joins the vertical groove at its 5 lower end.

Locking of the cover is effected by horizontally or laterally sliding it on its pintle so that its hemmed edge 23 moves into engagement with the body end wall 15. This movement causes the 10 cover locking lugs 34 to move into the horizontal bayonet grooves 37, thus locking the cover when in that position against opening by hinging action, see Fig. 2. In this position the hinge lug 31 is against one of the pintle lugs 26, see Fig. 3.

15 The cover in its locked position is held against longitudinal sliding displacement by an auxiliary locking projection 41 formed between the lugs 34 in the cover flange front wall 22 and a cooperating auxiliary locking indentation 42 formed in 20 the body front wall 16 between the bayonet indentations 35. These auxiliary locking elements move into locking engagement one within the other (Fig. 5) simultaneously with the interlocking of the bayonet indentation 35 and cover lug 25 projections 34. An inclined pocket or depression 43 formed in the body front wall 16 facilitates the moving of the projection 42 over the edge when first closing the cover.

To open the container it is merely necessary 30 to apply slight horizontal or lateral sliding pressure to the cover in a reverse direction to disengage the auxiliary locking elements 41, 42 and to move the cover locking lugs 34 out of their bayonet grooves 37. A finger grip depression 45 formed in the cover top wall 21 is provided to facilitate this sliding movement. After thus 35 unlocking the cover, it may be readily raised into open position by swinging on its pintle.

It is this combination of sliding and hinging 40 movements utilizing a flanged cover container locked in closed position by bayonet joint projections and indentations and auxiliary locking projections and indentations that inject a slight complication to the opening of the container.

45 This is of advantage when the container is used for medicine, etc., as it provides a fool proof feature. For example, a baby or very young child would not be able to open the container and such construction therefore provides a safe 50 container for contents which are of a nature to be kept out of reach of small children.

It is thought that the invention and many 55 of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container comprising a body having an open top, a cover for said body hingedly connected therewith along one side and laterally 65 movable relative to said body along the hinge connection, and cooperating projections and indentations formed in said cover and said body and adapted to be interlocked by said lateral movement, said body and cover having mutually 70 engaging flange walls on three sides of the container to permit and limit the sliding of the cover.

2. A container comprising a body having an open top, a cover for said body hingedly con-

nected therewith along one side and laterally movable relative to said body along the hinge connection, cooperating projections and indentations formed in said cover and said body and adapted to be interlocked by said lateral movement, and cooperating auxiliary projections and indentations in said cover and said body for holding said first mentioned projections and indentations in interlocked position, said body and cover having mutually engaging flange walls on 10 three sides of the container to limit the sliding of the cover excepting in a direction parallel with the hinge connection. 5

3. A container comprising a body having side walls and an open top, a cover for closing the 15 open top of said body and having depending flange walls on three sides only of the cover adapted to overhang corresponding body side walls when the cover is in closed position, said cover being hingedly connected with said body 20 along one side thereof and laterally movable relative to said body along the hinge connection, and cooperating projections and indentations formed in said cover flange wall and in the corresponding body side wall and adapted to be 25 interlocked by said lateral movement.

4. A container comprising a body having side walls and an open top, a cover for closing the open top of said body and having a depending 30 flange wall adapted to overhang a corresponding body side wall when the cover is in closed position, said cover being hingedly connected with said body along one side thereof and laterally movable relative to said body along the hinge connection, cooperating projections and indentations formed in said cover flange wall and in the corresponding body side wall and adapted to be 35 interlocked by said lateral movement for locking the cover and body together, and cooperating auxiliary projections and indentations 40 also formed in said cover flange wall and the corresponding body side wall for holding said first mentioned projections and indentations in interlocked position.

5. A container comprising a body having side 45 walls and an open top, a cover for said body hingedly connected therewith along one side and laterally movable on its hinge connection, said cover having a depending peripheral flange wall adapted to overhang said body side walls when the cover is in closed position, said flange wall being cut away adjacent one of said body side walls to permit said lateral movement of the cover on its hinge connection, and means associated with said body and said cover for locking 55 them together when the cover is in closed position.

6. A container comprising a body having side walls and an open top, a cover for closing the open top of said body and having a depending 60 flange wall adapted to overhang a corresponding body side wall when the cover is in closed position, said cover being hingedly connected with said body along one side thereof and being laterally movable relative to said body and along 65 the hinge connection, L-shaped bayonet indentations in a said body side wall, and cooperating lug projections in a said cover flange wall, said lugs being adapted to be interlocked with said bayonet indentations when the cover is brought 70 into its closed and laterally shifted position.
